APPARATUS FOR REDUCING SCALE FORMATION

Cornelis Hendrik van Toorn, Tiel, Netherlands,
assignor to N. V. Koninklijke Metaalwarenfabrieken v. h. J. N. Daalderop & Zonen, Tiel, Netherlands

Application October 15, 1949, Serial No. 121,583
In the Netherlands October 29, 1948

3 Claims. (Cl. 259—72)

1

Several proposals have been made for preventing the forming of incrustation in a chemical or electrolytic way. Such arrangements are however so extensive, that they can practically only be considered for steam boilers of high capacity. Moreover these installations are so complicated and expensive in the upkeep, that the same are practically not practised. Often one is content for scaling the incrustation from time to time, this being—especially in water tube boilers—very difficult and expensive.

For cooking—and heating apparatus of less capacity as geysers or electric boilers, which are very sensitive to the forming of incrustation there exists practically no protection against combating the forming of this troublesome incrustation in a suitable manner.

The object of the invention consists in providing an apparatus for preventing suitably the forming of incrustation in all heating apparatus, wherein water is brought at a high temperature. For this purpose water vibrations are excited with a low frequency of e. g. 20-90 cycles per second. These vibrations may be generated in any manner but it is practical to use for this purpose a membrane excited by an electromagnet connected to a normal mainsfrequency of 50-60 cycles per second.

Such an electromagnetically excited vibrating membrane has still another advantage that will appear from the following description, in which in view of the annexed drawing some forms of execution according to the invention are elucidated. Herein shows:

Fig. 1 a scheme of a vibrating system combined with a protection against excess pressure in the boiler;

Fig. 2 a scheme of a vibration system combined with another protection against excess pressure in the boiler.

In Fig. 1 the boiler is indicated with 1; the membrane 2 is watertightly mounted against the innerwall e. g. the bottom and is brought into vibration by an electromagnet with a U- or M-shaped core 4 the winding 5 of which is connected to the terminals 3 of an alternating mains with the normal mainsfrequency of 50-60 cycles per second.

In the practice it has appeared that the deposit of incrustation is obviated practically completely by the excited vibrations; so the tinned inner surface of an electrical boiler rests completely uncovered below the water level, whilst above the water level a slight deposit takes place.

The anti-incrustation arrangement applied to boiler may suitably be combined with an excess-

2

pressure-protection. For this purpose normally an automatic device for overpressure is used consisting in an elliptical metal tube, in which two spring contacts are situated at some distance from each other. When excess-pressure takes place the elliptical tube is pressed in and the spring contacts upon each other, so that an electric circuit is closed causing the cutting off of the heating body.

10 In the arrangement of Fig. 1 this overpressure-protection takes place as follows:

Upon one of the legs of the iron core 4 an insulated contact 7 is mounted cooperating with an earthed contact 6 upon the membrane 2. Under normal working pressures the membrane 2 has the possibility to vibrate freely with the mains-frequency, the contacts 6 and 7 are separated. When overpressure appears, the membrane 2 is pressed downwardly so far, that the contacts 6 and 7 will touch each other and a circuit is closed: null-terminal 3—upper knife switch 10—membrane 2—contact 6—contact 7—cut off coil—lower knife switch 10—R terminal 3. The excited coil 8 draws switch out of the locking catch 9, after which the spring actuated knives are cut off and the working current for the heating body 11 is cut off. During this action the circuit for the vibration magnet rests closed also after the cutting off of the heating elements.

30 In the scheme according to Fig. 2 the membrane 2 inside the boiler 1 is brought into vibration by an electromagnet with U-shaped core 4 the coil 5 of which is connected to the secondary coil 14 of a combined transformer relay the primary coil 13 of which is connected via the switch 10 to the mains terminals (50-60 cycles per second). The core 12 of the relay is M-shaped and both coils are preferably placed upon the middle leg. The spring actuated armature 16 is withdrawn in the normal working position because a current of sufficient highness runs through the secondary coil 14 and the magnet coil 5. Consequently the contacts 15 are opened and the heating body 11 is cut in.

45 By the increasing of the pressure in the boiler 1 the membrane is further pressed down, whilst it is still vibrating, so that the reluctance of the coil increases continually and the secondary current, flowing through the coils 5 and 14, fails gradually. At a predetermined value of this current the armature 16 attracted, the contacts 15 are separated and the heating body 11 is cut off.

It is clear that in the described connections different variations may be made without falling 55 beyond the frame of the invention.

What I claim is:

1. Apparatus for reducing scale formation upon the inner surface of a heated hollow vessel containing therein a liquid, including a flexible membrane formed of paramagnetic material, forming a portion of the lower wall of said vessel, and having one side thereof in contact with said liquid, an electromagnet so located as to present at least one pole piece thereof closely adjacent said membrane, and means for exciting said electromagnet by alternating current of a frequency at which said membrane is capable of oscillation.

2. Apparatus according to claim 1, in which said membrane also functions as a pressure-actuated heat control, there being provided a fixed contact upon said electromagnet and a movable contact upon said membrane, so juxtaposed that excess pressure within said vessel will flex said membrane and will close said contacts together, and relay means whereby said closure cuts off 20 the supply of heat to said vessel.

3. Apparatus according to claim 1, wherein the vessel is electrically heated and the exciting means for said magnet include a transformer-relay having a primary connected to said alter- 25

nating current and a secondary connected to said magnet, an armature magnetically adjacent the core of the transformer, so biased as to move to and from the transformer in accordance with current flow in said secondary, and bearing thereupon a first contact, and a second fixed contact cooperative with the armature contact, whereby abnormal approach of said membrane to said magnet will alter current flow through said secondary, and thereby will cause said armature so to move with respect to the transformer as to open said contacts, said contacts being connected in series with the electrical heating circuit for said vessel.
